UNITED STATES PATENT OFFICE.

DEWEY F. ADAMS, OF PROVIDENCE, RHODE ISLAND.

GEM-SETTING.

SPECIFICATION forming part of Letters Patent No. 270,921, dated January 23, 1883.

Application filed October 28, 1882. (No model.)

To all whom it may concern:

Be it known that I, DEWEY F. ADAMS, of the city and county of Providence, and State of Rhode Island, have invented a new and useful Improvement in Stone-Set Plated Jewelry, 5 of which the following is a specification.

My invention relates to a gem-setting for jewelry—such as an ear-ring or button—the face member of which consists of a setting composed of metal known as "stock-plate," in the form of a base or back having an upwardly-projecting integral wall or flange, and of a stone having a beveled edge or side inserted into said setting from the face side thereof and secured therein. In articles of jewelry thus formed it has been common to secure the stone in its setting by cement, by burnishing or slightly bending inward the upper edge of the wall or flange of the setting, or by knurling or indenting said edge to produce slight inward projections which shall engage the beveled side or edge of the stone and hold the same in place. By all these methods of securing the stone in its setting the brass or other base 25 metal composing the greater portion of the "plated stock" of which the setting is made comes to view on the upper edge of said flange or wall and soon becomes oxidized, thereby presenting an unsightly appearance.

My improvement consists in securing the stone in its setting by soldering to the upper edge of the wall or flange of the setting an annulus or rim, of gold or other superior metal, in such a manner as to cover from view the base metal on the edge of the flange, and so that said annulus or rim shall project inwardly from the flange and engage the beveled edge or side of the stone and secure it in position.

Referring to the drawings, Figure 1 represents in perspective an ear-ring embodying my improvement. Fig. 2 shows a section of the same on an enlarged scale.

A is the "setting," which is composed of stock-plate formed of base metal *a* and superior metal *b*. This setting is in the form of a 45 cup having a bottom plate, A', and an integral wall or flange, A².

C is the stone, having a beveled edge or side.

D is the annulus or rim, of gold or other superior metal, which may be very thin. After 50 the stone C has been inserted into the setting A, from the face side thereof, the annulus or rim D is secured by soft solder to the edge of the flange A², so as to cover the base metal *a* of said flange, and so as to project inwardly 55 therefrom and engage the stone, as shown in Fig. 2. By this construction only superior metal comes to view or wear on any part of the face member of the article, and an appearance closely resembling an article made of "solid" 60 superior metal is obtained. The face of the annulus or rim D may be ornamented in any preferred manner, and effects be thereby secured which could not be obtained by the common constructions, where the edge of the flange 65 A² is simply bent inward or knurled.

What I claim, and desire to secure by Letters Patent, is—

As a new article of manufacture, a gem-setting for jewelry, consisting of a cup-shape setting of plated stock, composed of a back-plate, A', and a wall or flange, A², a stone having a beveled edge inserted into the setting from the face side thereof, and an annulus or rim, D, of superior metal, which covers the edge 75 of the flange A², and is secured thereto, after the stone has been inserted, for the purpose of holding the stone in place, substantially as set forth.

DEWEY F. ADAMS.
